UNITED STATES PATENT OFFICE.

WILLIAM ERASTUS WILLIAMS, OF CHICAGO, ILLINOIS.

METAL FASTENER.

1,338,411.

Specification of Letters Patent. Patented Apr. 27, 1920.

Application filed April 24, 1918. Serial No. 230,410.

To all whom it may concern:

Be it known that I, WILLIAM ERASTUS WILLIAMS, a citizen of the United States, and a resident of Chicago, county of Cook, 5 State of Illinois, have invented a new and useful Improvement in Metal Fasteners, of which the following is a specification.

My invention relates to a type of fasteners, shown in my Letters Patent No. 10 1,201,008, of October 10, 1916, and used chiefly to bind end wood sections together to keep them from splitting and to bind 15 separate sections together. The object of the present invention is to produce a strip for a fastener that may be more easily rolled than other sections of the type mentioned.

Reference will be had to the accompanying drawing in which,

20 Figure 1 is a plan of my strip.

Fig. 2 is a section on line 2—2 of Fig. 1.

Fig. 3 is a section on line 3—3 of Fig. 1.

Fig. 4 is a section on line 4—4 of Fig. 1.

Fig. 5 is a plan of a modified form.

25 Fig. 6 is a section on line 6—6 of Fig. 5.

Fig. 7 is a section on line 7—7 of Fig. 5.

Figs. 2, 3, 4, 6 and 7 are on a larger scale than Figs. 1 and 5.

In the drawing, 2 indicates the body of 30 the fastener strip, 3 its sharp or cutting edge, 4 its driving edge or back, and 5 the cross ribs.

The cross ribs 5 do not extend fully across the strip but terminate at 6 near the driving 35 edge and at 7 near the cutting edge.

This leaves a space 8 on the driving edge and a space 9 on the cutting edge that is smooth and free from the cross ribs.

The modified form shown in Figs. 5, 6 40 and 7 differs from that of the other figures

only as relates to the cross ribs 5. In the modified forms the cross ribs on one face are opposite the spaces between the ribs on the opposite face of the strip instead of opposite each other.

45 In rolling strips of this class, where in order to hold properly against longitudinal slipping in the wood the ribs must rise abruptly from the body of the strip, the grooves in the rolls wherein the ribs are 50 formed, tend to hold the strip to wind on the rolls, and thus, when the cross ribs are of the desired shape, it is hard to roll the strip at all.

By leaving the blank spaces 8 and 9 on 55 the edges of the strip scrapers or lifters may be arranged to run along these spaces and force the strips from the rolls as fast as they are formed, thus making the rolling of this strip less difficult. I may leave a 60 smooth narrow face along the central body of the strip omitting the ribs on this zone, and apply the roll-scraper at this place, but I prefer to leave smooth portions at both edges of the strip.

65 I claim:

A thin rolled fastener strip having transverse ribs rising abruptly from its broader faces and extending only partly across the strip, whereby the strip has a continuous non-ribbed longitudinal portion along which lifting members may act to separate the strip from the forming rollers.

70 Signed at Chicago, county of Cook, and State of Illinois the 22nd day of April, 75 1918.

WILLIAM ERASTUS WILLIAMS.
